UNITED STATES PATENT OFFICE.

GEORGE W. MILLER, OF MERIDEN, CONNECTICUT.

HANDLE FOR POCKET-KNIVES.

SPECIFICATION forming part of Letters Patent No. 240,749, dated April 26, 1881.

Application filed December 16, 1880. (No model.)

To all whom it may concern:

Be it known that I, GEORGE W. MILLER, of Meriden, in the county of New Haven and State of Connecticut, have invented a new and useful Improvement in Handles for Pocket Instruments, (which has never been patented to any person in any foreign country with my knowledge and consent,) of which the following is a specification.

10 The object of my invention is to produce a cheap handle for knives and other pocket instruments, punched from metal and bent into such form as to hold the blade and the back-spring and be itself held in its proper form for 15 a handle, and all with only a single rivet; and I accomplish this object by the means and in the manner illustrated in the accompanying drawings, in which—

20 Figure I is a plan view of the handle-blank as it appears after being stamped out by means of a die. Fig. II is a side view of the handle after being bent into proper form to receive the blade or other instrument and the back-spring. Fig. III is a side view of the back-spring; and Fig. IV is an edge view of a knife, 25 looking into the handle.

In the drawings, 1 represents the handle-blank punched out from any sufficiently flexible and still rigid metal—such as sheet-steel, sheet 30 iron, brass, or any composition metal adapted to be bent into its desired form—and with the recesses or slots 3 and 5 also punched therein; but the general form of the blank may be punched out first, if desired, and the recesses 35 3 and 5 and holes 6 for the rivet punched afterward, if desired, the recess 3 having oblique or inclined ends 4, or an equivalent thereto, as hereinafter explained. After the blank 1 is punched into this form it is doubled or bent 40 nearly together lengthwise at a point midway its width, and a matrix being inserted into the open part of the handle edgewise, the extreme ends 2 of the handle are pressed-firmly together by means of a die or otherwise, so that 45 said ends 2 shall be quite near together, or in contact, to form the end of the handle, as shown clearly in Fig. IV. When thus formed, the back-spring 8, made of suitable spring-metal, and provided at the end with the inclined shoulder 9, (or its equivalent, according

to the shape of the shoulder 4,) is inserted into the open edge of the handle with the inclined shoulder 9 in the recess 3 of the handle, and the back-spring is forced back into the handle and against the back 7, and the heel of the 55 blade 10 is then inserted in the handle against the back-spring, and the rivet inserted in the holes 6, which holds the blade firmly in place. As thus secured in place the back-spring cannot be moved out of position in any direction 60 as long as the blade is held in its position by its rivet. When the blade is open the spring resists the pressure of the blade lengthwise by its bearing against the shoulder 13, and it cannot move directly out of the open front of 65 the handle, on account of its bearing against the shoulder 4, and the latter being inclined, and the inclined shoulder 9 on the spring, also prevents it from moving or being drawn out lengthwise toward the blade by the action of 70 the latter in being closed.

It is evident that instead of the inclined shoulder 4, any other shouldered form desired may be given to the recess 3, and the end of the back-spring be formed accordingly to enter 75 and properly fit said recess, when the ends 2 of the blank are bent together to form the handle, to prevent the back-spring from moving lengthwise in either direction, or out of the handle, away from its back; but the inclined 80 shouldered recess answers the purpose very well, and is easily made.

Before the blade is inserted the two ends, in which are made the holes 6 each side the slot 5, are bent a little nearer together than the 85 main part of the handle, so that that end of the handle may fit up closely and hug the sides of the heel of the blade to give stiffness and sufficient side bearing to the blade, as shown clearly in Fig. IV. The slot 5, however, is not 90 essential, as, if the blade is made stout and thick, to fill the handle properly, it will be sufficiently rigid and stiff; but in the manufacture of very cheap knives, by using the slot 5 I am not obliged to fold or double the sides of 95 the main part of the handle so near together, but can leave it more open and give it more fullness to fill the hand.

Of course the handle may be made to receive more than one back-spring, with a correspond- 100

ing number of blades or other instruments; and the end 2 of the handle may have any desired form, either curved or angular.

It will be seen that the spring is held firmly 5 in its position at its shouldered end by shoulders of the recess 3 and the pressure of the heel of the blade or other instrument against the opposite end of the spring, the bearing of the spring against the back 7 of the handle 10 inside being at any desired point toward the shouldered end of the spring.

It is evident that the handle, as thus arranged, is adapted to contain one or two instruments for a great variety of uses, and may 15 be carried in the pocket and used as a pocket-knife is used, when desired, such as button-hooks, belt-awls, reed-hooks, &c., each, of course, being formed similar to a knife-blade at the heel, to be riveted to the handle in the 20 same manner; and the sides of the handle may be more or less rounded, if desired, or the

handle given any desired shape in its cross-section, according to the shape of the dies used in forming it.

Having thus described my invention, what 25 I claim as new is—

A handle for pocket instruments having its sides and back formed of flexible metal in a single piece, and provided with a shouldered recess at one end, the said shoulders of which 30 recess are bent or brought together to secure and form a bearing for the correspondingly-shouldered end of the back-spring, and with the other end of said handle adapted to have the heel of the cutting or other instrument 35 riveted therein and press against that end of the back-spring, substantially as and for the purpose described.
